UNITED STATES PATENT OFFICE

MAX HANDSCHIEGL, OF LOS ANGELES, CALIFORNIA, ASSIGNOR TO BESSIE HANDSCHIEGL, OF LOS ANGELES, CALIFORNIA

DOUBLE EXPOSURE PROCESS

Application filed September 30, 1925. Serial No. 59,587.

This invention relates particularly to a double exposure process adaptable for use in the production of motion picture films; and it is a primary object of this invention to enable overlapping components of pictures to be taken, with satisfactory results, at different times and places.

As mentioned in my Patent No. 1,840,669 issued January 12, 1932, (in which I disclosed the best method which I had perfected previously to the filing thereof,—the process of the present application being a substantial improvement) it is often desirable, in the production of motion pictures, to combine several actions on one film; in other words, it is often desirable to photograph a figure or subject which constitutes one action, and then to photograph, upon the same film, a second scene or action, taken at another time or place,—making it appear, in the final production, that both actions occurred simultaneously or that the first mentioned action was taken with certain scenery or a background appropriate to the desired general effect.

As mentioned, it is an object of this present invention to provide improved methods whereby a figure or an object may be photographed in one location and under conditions which leave part of an original sensitized film unexposed the partially exposed film being afterward taken to another location, a second scene or other action may be there photographed upon the same negative, all operations being so executed as to make the two light impressions which the film has received cooperative and non-interfering in their effect.

It is a further object of this invention to provide a process of the general character indicated which shall be of greater simplicity, reliability and precision than any process now employed for a similar purpose, and by which the separate actions may be made accurately to register, so that hazy effects and poorly defined outlines are avoided.

Various special advantages of my invention, and further objects thereof, will be made evident in the course of the following description of a typical embodiment thereof, taken

in connection with the appended claims and the accompanying drawings, in which

Fig. 1 is a diagrammatic view showing a preferred manner in which a first figure or action may be photographed upon a pair of negative films, the image on one of these being reversed in a right-to-left sense.

Figs. 2 and 3 are enlarged views of cooperating frames from the two films, only the latter being shown as developed.

Fig. 4 is a diagrammatic view showing one manner in which a second scene may be photographed upon the sensitized film of Fig. 2, carrying an undeveloped image, the developed image of Fig. 3 (or a special positive herein-after mentioned) being used as a mat during this operation.

Fig. 5 is a view of a positive print from the film shown in Fig. 2, after this film has received the photographic image of the second scene, and has been developed as an original.

Figure 6 is a diagrammatic view illustrating the manner of enlarging, diminishing, or shifting the position of the image on a print made from the developed film.

Referring to the details of that specific embodiment of my invention chosen for purposes of illustration, I may employ a pair of negative films A and B, these being so exposed in a suitable camera that the photographic image of a figure, such as that of a dancing nymph 11, in action before a colored curtain 12, as for instance a red curtain, or another special background, is simultaneously light-impressed upon both films.

In the present embodiment of my invention, the construction of the camera C is such that photographic images exhibiting exact right-to-left or mirror symmetry of the figure 11 are simultaneously impressed upon the two films A and B, the inner faces *a* and *b* thereof being provided with usual or special sensitizing emulsions, adapting the same to be subsequently used face to face in a manner favorable to the avoidance of parallax, and the two films being advanced, at exactly the same rate, in such manner that the latent images occupy exactly corresponding but symmetrical positions.

Although analogous results, less perfect than those achieved by the construction herein described, may conceivably be accomplished by the use of double camera arrangements of known types, I consider it highly advantageous to employ a camera having a single opening for the admission of light, the interior organization of said camera being such as to provide exactly equivalent light paths and such as to enable me to run the mentioned films parallel, one placed at right angles to the other, substantially as shown,—said films respectively receiving a direct image and a once-reflected image from a semi-transparent mirror 13. In this manner, after the light from the object 11 traverses any desired lens in an entrance opening, a predetermined part thereof may pass directly through the said mirror and through a high speed lens or lens system 14, to be received by the film B; and another part, which may be substantially equal or of greater intensity, is reflected through a substantially identical lens or system 15 and is received by film A; an exact but counterpart or symmetrical duplication of the light impressions being thereby obtained.

It being assumed that in a certain motion picture production the representation of a dancing wood nymph is desired, it will be appreciated that it is not always practicable to take such an action directly upon the location of a suitable woodland scene; or that it may be desirable to reduce the proportions of the dancing figure to fairylike dimensions, or to exaggerate the same to gigantic proportions relatively to such a scene; and, accordingly, the nymph 11 being first photographed upon the respective films in the general manner described, the desired scene or background may be subsequently photographed, by the practice of my invention, at a different location. One of the mentioned films, as the film A, having latent images produced by reflection from the semi-mirror 13, is then developed, or over developed, to produce a "mat" suitable to be applied for the protection of the latent direct image produced, as described, upon the film B.

In Fig. 2 the dancing figure 11, which has been light-impressed upon the sensitized film B, is indicated by dotted lines 11a, whereas the film A, shown in Fig. 3, after receiving an exactly symmetrical light impression, has been developed in contrast, as shown at 11b. By "contrast" is here meant the development of an image by a so-called reversing process so that it will receive a comparatively heavy deposit of silver and will stand out from the surrounding area 16 and will be of pronounced opacity, interfering greatly with the passing of light rays through those areas upon which the image of the dancing figure 11, or its equivalent, was produced, but permitting the free passage of light through said surrounding area 16.

It should be understood that the film B, up to the moment here referred to, has remained undeveloped; and that the entire emulsion surface *b* thereof is still in a sensitized condition; and the next step in my process is to place the developed reversed film A, with its face downward or inward, upon the undeveloped film B, (those surfaces, *a* and *b*, which were originally provided with sensitizing emulsion being now preferably in actual contact) so that the light impressed image, indicated by dotted lines in Fig. 2, will be practically covered and protected by the described "mat" in the form of a contrast-developed and reversed image upon the film A. At a suitable location, or before a selected background 17, see Figure 4, these films are then "run" together (with their images face to face) through the same or another camera, substantially as indicated in Fig. 4, the desired additional scene or action being thus photographed upon the film B, through the clear area 16 which surrounds the developed image 11b. Since the said developed image substantially prevents the passage of light therethrough and since the two films A and B were simultaneously light impressed with the image of the figure 11, the image 11b will exactly register with the undeveloped image 11a and therefore prevent any further exposure of the latter image at this time.

As indicated in Figure 4, the scene or action which is subsequently to be employed as a background for the first action typified by the wood nymph or other object 11, may be an actual scene taken on location in a forest or it may be a picture such as an oil painting or a print. In Fig. 4 for the purpose of simplicity in illustrating the invention I show the selected background 17 as having a scene 18 painted or sketched thereon; and I assume that the camera used is focused upon the mentioned picture, without further regard to the original focusing than may be required in order to obtain a desired relative scale; and the scene 18 is light-impressed upon the area 19 of the undeveloped film B, which area surrounds the latent image indicated by the dotted lines 11a thereon.

Any desired tests may be made, at the beginning of the described second run, as by cutting off and developing a few frames, to be sure the light directions and intensities and also the durations of exposure are correct.

The films A and B are then removed from the camera; and the film B is developed. The resultant film, which is an original and not a "dup" negative, will contain the image of the first action, indicated in Figs. 1 and 2; and it will also contain the image of the scene 18 depicted on the picture 17 in Fig. 4. Therefore, a positive film 19' printed from the developed negative prepared from film B, will show, as suggested in Fig. 5, a positive image

11c illustrating an action as occurring in the setting or before the background 18c implied by the scene 18,—with the result that when this positive object is projected, the figure 11, whether upon a natural or a reduced or an enlarged scale, will appear as having been in action before the background or in the environment indicated by the said scene 18.

I have suggested that the background or scene which is employed in the second and conjoint use of the films A and B may be a picture or an actual scene; but it should be understood that I may alternatively employ, instead of such a background or actual scene, a previously taken positive of a scene or action, the impression thereof being accomplished in any preferred known way involving a transmission of light through the mat film A onto the second film B.

Instead of using the developed film A directly as a "mat" to protect the originally exposed portion of film B, during the second running thereof, I may follow an alternative course (see Fig. 6) including an intermediate production of a positive, A'. This course permits of not only limited readjustment of the positions of the mat images relative to the lateral side and the sprocket holes of the mat film but also any desired slight enlargement or diminution of the mat images, as by means of suitable spacing and positioning or by means of a suitable lens or lens system L, to make them exactly suitable to their intended purpose.

By employing a colored background 12 as distinguished from a white or a black background, and by further employing appropriate screens or color filters, the background is photographed "in" on one of the sensitized films, and is photographed "out" on the other sensitized film. In Figure 1 of the drawings there has been shown a red background 12, and a red screen or filter in front of the film A, so that the actinic reflected rays from the red background 12 will photograph "in" the background on film A, while the green screen or filter placed before the film B will absorb the actinic rays from the red background 12 and result in photographing "out" the background on the film B. Having photographed "out" the background 12 on the film B, it is the image or object 11 only which is photographed or light impressed upon the film B, thereby leaving the remaining sensitized portions of the film unchanged and therefore capable of subsequently being light impressed or photographed upon. By photographing "in" the background on film A, both the background 12 and the image or object 11 are photographed or light impressed on the film A. Then by developing the film A, having the figure and the background photographed thereon, a silhouette print may be made therefrom so as to obtain a clear transparent background around the image,

said image portion being developed to a point where it will exclude light when employed in front of undeveloped film B in making the second exposure, as illustrated in Figure 4, before any suitable background so as to photograph said background through the clearly transparent portion of the silhouette and upon the undeveloped film B.

Instead of making a print silhouette from the film A, the negative film A may be made into a positive by development, and employed in the manner of the print silhouette, thereby avoiding the making of a print silhouette from the developed film A.

Inasmuch as the ordinary films are primarily sensitive to blue-violet color, by using a blue background, only one screen is necessary (a red filter) and that screen will be employed to photograph "out" the background on one of the films, the blue background being photographed "in" on the other film.

Although I have herein described alternative embodiments of my invention, it should be understood that various features thereof might be independently used, and that numerous modifications might be made, by those skilled in the art to which this case relates, without the slightest departure from the spirit and scope of my invention, as the same is indicated above and in the following claims.

I claim as my invention:

1. The herein described photographic method of producing composite motion pictures, which consists in simultaneously exposing two sensitized films to an object before a colored background and photographing the background "in" on one film through a filter which passes light rays from the background and "out" on the other film through a filter which absorbs light rays from the background, developing the film having the background "in", making an intensified print from the developed film, employing the print as a silhouette to the undeveloped film, and then photographing a background upon the undeveloped film through said silhouette.

2. The herein described photographic method of making mats for the production of composite motion pictures, which consists in simultaneously exposing two sensitized films to an object in front of a colored background and photographing the background "in" on one film through a filter which passes light rays from the background and "out" on the other film through a filter which absorbs light rays from the background, and reversing and intensifying the image on the film having the background photographed in thereon to produce a silhouette directly on said film.

3. The herein described photographic method of making mats for the production of composite motion pictures, which consists in

producing a negative of an object in front of a colored background and through a color screen or filter which transmits the colored rays from the colored background, and reversing the image thus obtained to produce a silhouette directly on said negative.

4. The herein described photographic method of producing composite motion pictures, which comprises simultaneously producing a negative and a right-to-left reversed negative in one and the same camera of an object in front of a plain colored background through color filters which photograph the background "in" on one negative and "out" on the other negative, developing the negative having the background "in", making an intensified print from the developed negative, employing the print as a silhouette to the undeveloped negative, and then photographing a scenic background upon the undeveloped negative through said silhouette.

5. The herein described photographic method of producing composite motion pictures, which comprises simultaneously producing a negative and a right-to-left reversed negative in one and the same camera of an object in front of a plain colored background through color filters which photograph the background "in" on the right-to-left reversed negative and "out" on the other negative, developing the reversed negative, making an intensified print from the developed reversed negative, employing the print as a silhouette to the undeveloped negative, and then photographing a scenic background upon the undeveloped negative through said silhouette.

6. The herein described photographic method of producing composite motion pictures, which comprises simultaneously producing a negative and a right-to-left reversed negative in one and the same camera and from a single point of view of an object in front of a plain colored background through color filters which photograph the background "in" on the right-to-left reversed negative and "out" on the other negative, developing the reversed negative, making an intensified print from the developed reversed negative, employing the print as a silhouette to the undeveloped negative, and then photographing a scenic background upon the undeveloped negative through said silhouette.

7. The herein described photographic method of producing composite motion pictures, which comprises simultaneously producing a negative and a right-to-left reversed negative in one and the same camera and from a single point of view of an object in front of a plain colored background through color filters which photograph the background "in" on one negative and "out" on the other negative, developing, reversing, and intensifying the image on the negative having the back-

ground "in" thereon to produce a mat film having a silhouette image, and then photographing a scenic background upon the other negative through said mat film.

8. In the making of composite motion pictures, the steps of simultaneously producing a negative and a right-to-left reversed negative in one and the same camera of an object in front of a plain colored background and through color screens or filters, the filter for one negative transmitting the color rays from the colored background and the filter for the other negative absorbing the color rays from the colored background.

9. In the making of composite motion pictures, the steps of simultaneously producing a negative and a right-to-left reversed negative in one and the same camera of an object in front of a plain colored background and through color screens or filters, the filters for the reversed negative transmitting color rays from the colored background, and the filter for the other negative absorbing the color rays from the colored background.

10. The herein described photographic method of making mats for the production of composite motion pictures, which includes the steps of simultaneously producing a negative and a right to left reversed negative in one and the same camera of an object in front of a plain colored background and through color screens or filters, the filter for one negative transmitting the color rays from the colored background and the filter for the other negative absorbing the color rays from the colored background, and reversing and intensifying the image on the film exposed to the color rays from the colored background to produce a silhouette directly thereon.

11. The herein described photographic method of making mats for the production of composite motion pictures, which includes the steps of simultaneously producing a negative and a right-to-left reversed negative in one and the same camera of an object in front of a plain colored background, photographing the background "in" on one film and "out" on the other film, and reversing an intensifying the image on the film having the background photographed "in" thereon to produce a silhouette directly on said film.

In testimony whereof, I have hereunto set my hand at Los Angeles, California, this 19th day of September, 1925.

MAX HANDSCHIEGL.
